BY *Ralph E. Slayton*

ATTORNEY.

UNITED STATES PATENT OFFICE.

MONIE A. FERST, OF DE KALB COUNTY, GEORGIA, ASSIGNOR TO SCRIPTO MANUFACTURING COMPANY, OF ATLANTA, GEORGIA, A CORPORATION OF GEORGIA.

CONTAINER.

Application filed February 12, 1924. Serial No. 692,218.

- This invention relates to containers and has more particular reference to a container or receptacle for holding reserve lead points designed for use in mechanical pencils.
- 5 The present invention aims to provide a durable container of enhanced appearance which can be economically produced and which will effectually serve its designed purpose.
- 10 Lead points for use in mechanical pencils are manufactured in different colors, and of varying degrees of hardness.
- In order to afford accommodation and to provide means for segregating these different kinds of points, the illustrated embodiment of the invention comprehends a plurality of lead receiving recesses formed in a suitable body portion; and in order to retain the lead points in the recesses, swivelled closure means are attached to the body portion, the attaching means serving as the swivelling means and the closure means comprising a rotatably mounted flat strip.
- 15 While a preferred embodiment of the invention is illustrated in the accompanying drawing, it is to be understood this embodiment merely serves to illustrate the underlying principles of the invention so that they may be readily comprehended by those skilled in the art and the embodiment is in no wise intended to limit the invention to the specific form disclosed.
- 20 In said drawing:
- Fig. 1 is a perspective view of an embodiment of the invention.
- 25 Fig. 2 is a vertical section of the embodiment shown in Fig. 1 and
- Fig. 3 is a top plan view of the embodiment shown in Fig. 1 with the closure member turned to a position at right angles to its closed position shown in Fig. 1.
- 30 Continuing by way of a more detailed description, a body portion A preferably consisting of an easily worked material, such as wood, has one or more vertical lead receiving apertures or recesses B, which are shown as circular in cross section because preferably they are formed by drilling, although the manner of their production is not restricted to this particular method, since the body portion might be molded.
- 35 The open or exposed ends of these recesses are preferably located on one side or face of the container, although this is not ab-
- solutely essential nor is it essential that the recesses terminate short of the bottom since they might extend clear through the body portion, the lower end being closed in any suitable manner as for example by a stub of material secured to the bottom.
- 40 One end of the lead receiving recesses B is closed by a swivelled closure member C arranged to rotate around a post or pin D, in a plane substantially parallel to the apertured side of the body portion. This closure member preferably consists of a substantially flat strip of metal having a depressed indent E adapted to lock with a notch E' formed in the body portion A when the strip C occupies its normal position, that is closing the apertures as indicated in Fig. 1. The closure strip C may also be and preferably is provided with a raised indent or finger hold F adapted to facilitate the manual manipulation of the closure member C, when it is desired to expose the apertures. The relation between the depth and shape of the notch E' and its cooperating elements is such that the indent E normally holds the strip E in its normal position and yet enables the strip to be rotated on application of suitable rotational pressure.
- 45 It is to be understood that the lead points are placed in the lead receiving recesses B and poured out when needed. The exposure of the apertures being regulated by rotating the closure member C. In order to permit the flow of lead points from the recesses, it is not essential, nor even in most cases desirable, that the closure member be completely turned to the position shown in Fig. 3 but it may only be partly turned from its normal position to a position as to expose but a portion of the recess B and thus restrict or limit the flow of leads, and permit but one point to be dropped out.
- 50 It is claimed:
1. A container for pencil leads comprising a body portion having a plurality of lead receiving openings, a flexible swivelled unperforated cover adapted to close the openings and a stationary pin to swivel the cover, the cover having a depressed portion adapted to frictionally lock with a latch opening in the body portion, the depressed portion being unlocked by rotation of the cover.
- 55 2. A container for pencil leads comprising a body portion having a plurality of

lead receiving openings, a flexible swivelled unperforated cover adapted to close the openings and a stationary pin to swivel the cover, the cover having a depressed portion adapted to frictionally lock with a latch opening in the body portion, and a raised portion adapted to afford a finger hold, the

depressed portion being unlocked by rotation of the cover.

Signed at Atlanta, in the county of De ~~10~~
Kalb and State of Georgia, this 30th day
of January, 1924.

MONIE A. FERST.
